SELF-OPERATING DRAUGHT EXCLUDER

Frederick Charles Wynne, Hounslow, England

Application January 3, 1944, Serial No. 516,825
In Great Britain January 23, 1943

3 Claims. (Cl. 20—68)

1

This invention relates to draught-excluding devices for doors, of the kind having a push rod actuated by the closing of the door to operate means for moving a draught-excluding member into the operative position.

The present invention comprises a draught excluder of this kind, in which the draught-excluding member is moved into position by the co-operation of cam surfaces on said push rod and correspondingly shaped cam surfaces on an associated part of the door and on said draught-excluding member.

According to the preferred embodiment, the device consists of a fixed bar adapted to be secured to the door and a movable bar supported from said fixed bar by double cam members which are mounted on the push rod and engage correspondingly shaped recesses in the fixed and movable bars respectively.

The invention will now be described by way of example with reference to the accompanying diagrammatic drawings, in which:

Figure 1 is a side elevation of the device before the draught-excluding member has been moved into position,

Figure 2 is a side elevation of the device after the draught-excluding member has been moved into position,

Figure 3 is an enlarged section on the line 3—3 of Figure 2, showing the device mounted on the door, and

Figure 4 shows the arrangement by which the device is actuated.

As illustrated, the device consists of a fixed bar 11 and a movable bar 12, the fixed bar 11 being fixedly mounted within a casing 13 which is secured to the door by means of lugs 14 and is open on the side facing the door and on the edge facing the surface beneath the door to allow face movement of the movable bar 12. The movable bar 12 is supported from the fixed bar 11 by means of two double cam members 15 which are connected together by means of a rod 16. A push rod 17 is pivotally secured to the front cam and passes through a vertical slot 18 in a bracket 19 which is secured in a recess in the fixed bar 11, and terminates in an actuating knob 20. Said knob, when the door is open, extends through an opening in the end of the casing 13. A coil spring 21 surrounds the push rod 17 and bears between the knob 20 and the bracket 19. The movable bar 12 is also recessed at one end to accommodate the actuating knob 20 and spring 21 when the door is open (Figure 1). Both the fixed and movable bars are formed with semi-

2

circular grooves 22 in their adjacent edges to accommodate the connecting rod 16 and the push rod 17 when the door is open and the device inoperative.

5 The arms of the cams 15 engage correspondingly shaped recesses 23 in the fixed and movable bars, the recesses 23 being provided with metal linings 26 to form bearing surfaces for the cams 15. A flexible tubular member 24 of rubber or 10 other suitable material is secured in a groove in the bottom edge of the movable bar 12 to ensure proper contact being made with the surface beneath the door.

It will be understood that the device is secured 15 to the door in a position depending upon the clearance between the door and the adjacent surface.

As shown in Figure 4, the device is actuated on closing the door by the knob 20 striking a 20 plate 25 on the frame of the door. The push rod 17 then forces said cams 15 out of the recesses 23, the pivotal connection between the rod 17 and the cams allowing the cams to move downwardly and out of said recesses whereby 25 the movable bar 12 is forced downwardly into a draught-excluding position. It will be noted that both arms of the cams 15 contribute to this movement whereby the extent of the downward movement of the movable bar 12 is increased. 30 The vertical slot in the bracket 19 permits of the necessary vertical displacement of the push rod 17 due to the movement of the cams 15 out of recesses 23.

The device, consisting of the fixed and movable bars, cams and cam-actuating means, need not be mounted within a casing. Thus, the fixed bar 11 may be secured within a recess formed in the appropriate edge of the door.

I claim:

40 1. A draught-excluder for a door, comprising a fixed bar adapted to be mounted on the door, a movable bar, a plurality of chevron-shaped cam members supporting said movable bar from said fixed bar by engagement with correspondingly 45 chevron-shaped recesses in the fixed and movable bars respectively, a rod of rigid material connecting said cam members to provide joint simultaneous action thereof, and a push rod pivotally connected to one of said cam members and actuated by the closing of the door to impart movement to said cam members, whereby the cams partially recede from the said recesses in the fixed and movable bars thus moving the movable bar downwardly into a draught-excluding posi- 50 tion.

2. A draught-excluder according to claim 12, in which the movable bar is returned into the inoperative position when the door is opened by means of a spring which bears between an actuating knob on said push rod and a bracket member housed within recesses in said fixed and movable bars, said bracket member being slotted to allow the passage therethrough of the push rod and also to permit of the necessary vertical displacement of the push rod due to the said joint movement of said cam members out of said recesses.

3. A draught-excluder according to claim 1 in which complementary grooves are formed in the adjoining edges of said fixed and movable bars to accommodate said connecting rod and said push rod in the inoperative position of the device.

FREDERICK CHARLES WYNNE.
